A. M. Allan Risk, A. M. Allan Risk, A. M. Allan Risk

UNITED STATES PATENT OFFICE.

ALLAN RISK, OF NEWCASTLE-UPON-TYNE, ENGLAND.

HAND-OPERATED APPARATUS FOR ROTATING DRILLS OR OTHER ROTARY TOOLS OR IMPLEMENTS.

1,257,532.

Specification of Letters Patent.

Patented Feb. 26, 1918.

Application filed August 28, 1917. Serial No. 188,586.

To all whom it may concern:

Be it known that I, ALLAN RISK, a subject of the King of Great Britain and Ireland, and resident of Heaton, Newcastle-upon-Tyne, England, engineer, have invented certain new and useful Improvements in Hand-Operated Apparatus for Rotating Drills or other Rotary Tools or Implements, of which the following is a specification.

10 This invention relates to hand-operated drill mechanism.

Apparatus made in accordance with this invention comprises two members pivoted together and adapted to be held in one hand 15 and to be moved angularly in respect of one another, a rotary spindle disposed on one member, and means for rotating the spindle when the pivoted members are moved toward one another.

20 I will fully describe my invention with reference to the accompanying drawings wherein—

Figure 1 is a front elevation of one construction of apparatus embodying my invention;

Fig. 2 is a view looking on the right-hand side of Fig. 1; and

Fig. 3 is a part similar view to Fig. 1 showing another position of the operating 30 rack.

Referring to the drawings, the embodiment of my invention therein illustrated comprises two members *a* and *b* pivoted together at *c*, one member *a* being an arm 35 carrying a sector *d* and the other member, *b*, a hollow rod, the axis of the pivot *c* being the center from which the sector *d* is struck. The hollow rod *b* is provided with a thumb-piece *e* and is adapted to receive a 40 spindle *f* which projects from each end thereof. The spindle *f* is free to rotate in the hollow rod *b* and is provided with a flywheel *g* mounted within a frame *r* carried by the hollow rod *b*. On the spindle *f* is fixed a pinion *h* which is engaged by 45 a curved rack *j* carried by a plate *j'* attached to the sector *d*, any lateral movement of said pinion except in a direction parallel to the rack *j* being prevented by a pin *s* 50 projecting rearwardly from the foot of the rod *b* engaging a curved slot *k'* in the sector *d*. The spindle *f* is provided with a chuck *m* at its outer end adapted to receive and hold a drill or other rotary tool or implement. The sector *d* is provided with a slot

or finger piece *n* at one end. The end of the hollow rod *b* opposite to that from which the spindle *f* projects is provided with a head of cap *p*.

The plate *j'* whereby the segmental rack 60 *j* is carried is provided with pins *t* the rear ends of which pass through parallel slots *d'* in the sector *d* so that said rack is capable of radial motion with respect to the pivot *c*. In front of the rack plate *j'* is a 65 plate *u* having a curved slot *u'* at each end through which passes a pin *x* fixed in the sector *d*. The rear face of the plate *u* is provided with two oblique grooves *v* in which engage the front ends of the pins *t* 70 of the rack plate *j'*.

In use the apparatus is gripped in one hand, the thumb fitting into the thumb-piece *e* on the hollow rod *b* while one or more of the fingers are passed through or 75 placed in the slot or finger piece *n* of the sector. By alternately closing and opening the hand the arm *a* carrying the sector *d* and rack *j* is caused to swing to and fro about the pivot *c*, the rack co-acting with 80 the pinion *h* during the closing of the hand, that is the power stroke, to rotate the spindle *f* and the drill or the like carried thereby. During oscillation of the sector *d* and rack *j*, when the abutment *w* on the plate 85 *u* comes into contact with the shoulder *y* on one side of the hollow arm *b*, the plate *u* is moved to the left and the co-action of its oblique grooves *v* with the pins *t* of the rack plate *j'* causes said rack plate to move 90 radially outward, as shown in Fig. 3, to disengage the rack *j* with the pinion *h*. The momentum of the flywheel *g* continues to rotate the spindle *f* while the operator's hand is opening. On the return stroke, 95 when the shoulder *y'* on the other side of the hollow arm *b* comes into contact with the abutment *v'* on the plate *u* this plate is moved over to the right and the co-action of its oblique grooves *v* with the pins *t* of 100 the rack plate *j'* causes said rack plate to move radially inward again and reengage the rack *j* with the pinion *h* ready for the next working stroke. In this way the direction of rotation of the spindle *f* is not 105 reversed, the flywheel having sufficient momentum to keep the spindle rotating when the pinion is disengaged from the rack. It will be found that sufficient pressure in an axial direction to cause the drill to enter 110

the work can usually be put upon the drill by the operating hand, but, if necessary, additional pressure in an axial direction can be put upon the drill by pressing with the other hand upon the head or cap *p* of the hollow rod *b*.

The size of the flywheel *q* may be varied to vary the power of the drill, as may also the size of the pinion *h* for the same purpose. To allow of this the hollow rod *b* may be so mounted on the pivot *c* that the position of its axis can be moved nearer to or farther away from the rack *j*. Or a series of interchangeable racks may be provided.

What I claim and desire to secure by Letters Patent is:—

A drill comprising two members pivoted together and adapted to be held in one hand

and to be moved angularly in respect of one another, a rotary spindle disposed on one member, and having a toothed pinion, flywheel and tool holder on said spindle, a segmental rack disposed on the other member adapted to engage the said pinion, means for bringing the pinion and rack into engagement with one another prior to making the power stroke, and means for bringing the pinion and rack out of engagement after the power stroke, all constructed and operating as herein set forth.

In testimony whereof I have signed my name to this specification.

ALLAN RISK.
